UNITED STATES PATENT OFFICE.

CHARLES WESLEY TREVERTON, OF SCRANTON, PENNSYLVANIA.

DESIGN FOR A SYRINGE.

SPECIFICATION forming part of Design No. 22,669, dated August 1, 1893.

Application filed April 29, 1891. Serial No. 391,015. Term of patent 7 years.

To all whom it may concern:

Be it known that I, CHARLES WESLEY TREVERTON, a citizen of the United States, and a resident of Scranton, in the county of Lackawanna and State of Pennsylvania, have invented certain new and useful Improvements in Vaginal Syringes; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a side view. Fig. 2 is a top plan view.

This invention has relation to a certain new and original design for vaginal syringes, and it consists in the novel form and 20 configuration thereof, all as hereinafter set forth and shown in the accompanying drawings.

In the said drawings, the letter C represents an elongated, oval, concavo-convex portion, from the center of which rises the portion A, terminating in a rounded portion a. Below 25 the rounded portion a, the portion A is flattened, as shown at B, and through this flattened portion is a semi-oval shaped opening b. From the convex under surface of the portion C, are two short, cylindrical, diverging portions d.

Having thus described my invention, what I claim is—

The design for a vaginal syringe as herein shown and described. 35

In testimony whereof I affix my signature in presence of two witnesses.

CHAS. WESLEY TREVERTON.
